UNITED STATES PATENT OFFICE.

HERMAN MACK, OF CHICAGO, ILLINOIS.

DESIGN FOR A BICYCLE-COVER.

SPECIFICATION forming part of Design No. 27,645, dated September 14, 1897.

Application filed June 28, 1897. Serial No. 642,759. Term of patent 7 years.

To all whom it may concern:

Be it known that I, HERMAN MACK, a citizen of the United States, residing at Chicago, in the county of Cook and State of Illinois, have invented and produced a new and original Design for Bicycle-Covers, of which the following is a specification, reference being had to the accompanying drawing, forming a part thereof.

10 This design relates to the configuration of a bicycle-cover, the accompanying drawing being a perspective view of a bicycle-cover embodying my design.

15 The distinctive feature of my design consists of the peculiar shape of the body portions of the cover and the depending flaps at the front ends of the body portions.

20 Referring to the drawing, A A represent the vertical side or body portions of the covering, each of which has substantially the form of a diamond, with its front point cut away or truncated similar to the diamond-shaped frame of a bicycle which it is intended to cover. The outline of each body portion

25 consists of a substantially horizontal upper edge a , a substantially vertical front edge a' , extending downwardly from its junction with the upper edge, an inclined lower edge a^2 , which extends rearwardly and downwardly

30 from the lower end of the front edge, and two inclined rear edges $a^3 a^4$, which converge from the rear ends of the upper and lower edges $a a^2$ and unite at their rear ends. The upper

edges of both body portions are united along the central portions, and the end portions 35 thereof are connected by fastenings B.

Each of the body portions is provided with inwardly-projecting flaps b between the point b' at the junction of the converging rear edges $a^3 a^4$ and the upper and lower points $b^2 b^3$ at 40 the junction of said rear edges with the upper and lower edges, said flaps being joined at their rear ends and decreasing in width from the point b' to the upper and lower points $b^2 b^3$. The inclined rear edges $a^3 a^4$ of both body 45 portions are connected by fastenings c , the lower edges a^2 thereof are connected by fastenings d , and the front edges a' thereof are likewise connected by fastenings d' .

$e e$ represent two depending flaps, which 50 extend downwardly and forwardly in a slight curve from the lower front portions of the sides of the cover, so as to conform to the shape of the members of the front steering-fork of the bicycle which it is intended to 55 cover. The lower ends of the depending curved flaps are provided with fastenings e' .

I claim as my invention—

The design for a bicycle-cover substantially as herein shown and described. 60

Witness my hand this 24th day of June, 1897.

HERMAN MACK.
